TORPEDO

James L. Bisch, United States Army,
Port Royal, Va.

Application September 13, 1945, Serial No. 616,139

5 Claims. (Cl. 102—22)

(Granted under the act of March 3, 1883, as
amended April 30, 1928; 370 O. G. 757)

1

The invention described herein may be manufactured and used by or for the Government for governmental purposes, without payment to me of any royalty thereon.

The present invention relates generally to a device for the destruction of enemy mines but more particularly to a snake demolition torpedo comprising an elongated container for explosive cartridges adapted to be pushed by a tank into mine fields or other obstacles to clear a path for advancing armies.

One object of the invention is to provide a mine clearing device which is of simple construction and one which may be assembled from readily available material with very little processing.

Another object of the invention is to provide a device of the class described which may be readily transported to the place of operation and then moved into position for the destruction of mines without danger to the operator.

Still another object of the invention is to provide a mine clearing device which is economical in construction, simple in operation and one composed of parts which may easily be transported to bases of operations.

Objects and advantages other than those above set forth will be apparent from the following description when read in connection with the accompanying drawings.

Referring to the drawings in which like parts are indicated by similar reference characters:

Figure 1 is a top plan view of the snake demolition torpedo;

Figure 2 is a side elevation of the torpedo shown in Fig. 1;

Figure 3 is a sectionized elevation of a portion of the torpedo, the section being taken on the longitudinal center line of Fig. 1;

Figure 4 is a cross-sectional view taken on the line 4—4 of Fig. 3;

Figure 5 is a perspective view showing one method of connecting the overlapping plates;

Figure 6 is a perspective showing another method of connecting the overlapping plates;

Figure 7 is a cross-sectional view showing a modified form of longitudinally curved body sections;

Figure 8 is a top plan view showing the forward end of a snake including the nose adapter end nose;

Figure 9 is a side elevation showing the forward end of the snake including the nose adapter and nose illustrated in Fig. 8;

Figure 10 is a side elevation of a modified form of nose;

2

Figure 11 is an end view of the modified form of nose illustrated in Fig. 10;

Figure 12 is a side elevation of another modified form of nose;

5 Figure 13 is a top plan view of the modified form of nose illustrated in Fig. 12;

Figure 14 is a top plan view of a portion of the snake type torpedo showing the alignment of the cartridges within the parallel channels 10 thereof;

Figure 15 is a partially sectionized view, the section being taken on the line 15—15 of Fig. 14;

15 Figure 16 is a sectionized view of a cartridge, the section being taken along a longitudinal center line;

Figure 17 is an end elevation of the cartridge shown in Fig. 16;

Figure 18 is a top plan view of the initiating unit, showing the shield, target button and location 20 of charge therein;

Figure 19 is a sectionized view of the initiating unit, the section being taken on the line 19—19 of Fig. 18;

25 Figure 20 is a partially sectionized end elevation of the initiating unit, the section being taken on the line 20—20 of Fig. 19;

Figure 21 is a top plan view of the rear hook and attaching bar;

30 Figure 22 is a partially sectionized side elevation of the hook and bar shown in Fig. 21, the section being taken on the longitudinal center line;

Figure 23 is an end elevation of the hook shown in Fig. 21, showing its attachment to a section 35 of the torpedo;

Figure 24 is a top plan view of a modified form of torpedo composed of spaced tubular sections;

Figure 25 is a partially sectionized view showing a cross bar coupling member, the section being taken on the line 25—25 of Fig. 24;

40 Figure 26 is a side elevation of a modified form of towing hook, as shown in Fig. 24;

Figure 27 is a side elevation of a modified form of pushing hook, as shown in Fig. 24;

45 Figure 28 is a perspective view showing a tank connected to the forward end of a torpedo to illustrate the manner of towing the same;

Figure 29 is a perspective view showing a tank connected to the rear portion of a torpedo to illustrate the manner of pushing the same; and

50 Figure 30 is a top plan view of the towing yoke.

Briefly stated, the snake demolition torpedo comprises an elongated container formed of either longitudinally bent strips of steel or long steel tubes which serve as conveyers for demoli-

55

tion cartridges and which may be towed by a tank to an intended locality of operation, pushed thereby into operative position, and the charges ignited by gun fire or electrical means.

The body of the snake is composed of a plurality of steel strips 10 and 10' bent longitudinally so that a cross-section taken anywhere throughout its length has the form of the letter W, as shown in Fig. 4. The snake is formed by bolting the elongated strips together centrally so as to provide parallel channels on either side of the center line thereof, as shown in Figs. 4, 5 and 6, and by uniting a plurality of such sections to form the elongated main portion of the snake. A modified form of corrugated or bent strips 11 and 11' may be used as shown in Fig. 7. To the forward end of the central portion or body is attached a yoke-shaped nose adapter 12, as shown in Figs. 1, 2, 3 and 9. The nose adapter is provided with two parallel limbs 13 and 13' which are inserted into the parallel channels 14 and 14' in the body of the snake and a third limb 15 to which is attached a nose 16 which is formed with a conical body 17 and a hemispherical deflector portion 18 as shown in Figs. 1, 2, 8 and 9. To the upper surface of the adapter 12, at the juncture of its limbs 13 and 13', is welded a splice plate 19 and to the splice plate 19 and the limb 15 is welded a towing hook 20. The limb 15 of the adapter 12 projects within an opening 21 in the nose 16, and the nose is connected to the towing hook 20 by means of a rope or wire loop 22 which passes through openings 23 and 24 in the hook and the nose, respectively, and through an eye 25 attached to the limb 15.

The towing hook 20 is adapted to be engaged by a towing yoke 26 connected to the rear portion of a tank or other vehicle as shown in Figs. 28 and 29. To the rear end section of the snake-torpedo is attached the rear or pushing hook 27 which comprises a diagonally projecting hook arm 28 connected to a longitudinal base 29 which is bolted or otherwise suitably attached to the rear section. The hook arm is capped by a retaining plate 30. The pushing hook is adapted to be engaged by a wire cable or chain connected to the forward end of a tank in order to move the snake into operative position after it has been towed to a desired location by the towing loop at the rear of the tank.

The bent or corrugated strips 10 and 10' which are united along their center line by bolts 32 form the channels 14 and 14' into which are placed the explosive cartridges 33 and sand bags 34, the sand bags functioning as ballast to retain the end portions of the snake, which are not filled with cartridges, in contact with the earth.

The sections of the snake overlap each other and are bolted together either centrally as in the type of casing shown in Figs. 1 to 6, inclusive, or laterally as shown in Fig. 7, which illustrates a modified form. In snake torpedoes which are formed of spaced parallel tubes, as shown in Fig. 24, the sections of the tubes are preferably welded together. The longitudinally arranged tubes 35 and 35' in the central portion of the torpedo are separated by spacer tubes 36 and bars 37. The tubes 35 and 35' are connected by bolted collars 38 and are welded at their extremities to tubes 39, 39' and 40, 40' which converge toward the central longitudinal axis of the snake where they are welded to centrally located tubes 41 and 42. The forward tube 41 is connected by a bolted coupling 43 to a tube section 44 on which is mounted a forward skate hook 45. The rear

centrally located tube 42 is connected by a coupling 46 to a tube section 47 on which is mounted a rear skate hook 48. The skate hooks comprise sleeves to which are connected an upright projecting hook and laterally projecting fins as illustrated in Fig. 26 and 27. In the forward or towing hook 45 the hook member comprises an upper diagonally projecting hook arm 49 connected to a longitudinal base 50 which is attached to the sleeve 51. The rear or pushing hook 48 has a similar diagonally projecting hook arm 52 which is capped by a flat retaining plate 53. The arm 52 is connected to a base 54 which is attached to the sleeves 55. The hook members 45 and 48 are provided, respectively, with laterally projecting fins 56, 56' and 57, 57'.

Several types of nose pieces may be used with the snakes, one type being the nose illustrated in Figs. 8 and 9, which is formed with a conical body or rear portion 17 and a hemispherical head portion 18. The head portion may be made up of a plurality of hemispherical sectors or formed in a single piece as shown. A modified form of nose is shown in Figs. 10 and 11. This form of nose is formed by turning the forward portion of the lower front corrugated section of the snake upwardly either by bending or forming the upturned portion in several parts 58 and 59 which are riveted or welded together and braced by members 60 as shown in the illustrations.

Another modified form of nose is illustrated in Figs. 12 and 13. In this type the nose member 61 comprises a sloping arm 62 which is connected to a nose adapter 63. Through an opening 64 in the arm 62 is rotatably mounted a shaft 65 to the ends of which are attached the hemispherical rolling members 66 and 66'. An arcuate shaped guard member 67 is attached to the arm 62 to partially close the opening between the hemispherical rollers.

Connected to the upper corrugated sections of the snake-torpedo in the forward and rear portions of its body are located target shields 68. The target shields comprise a curved and tapered cover plate 69 which is bolted to an upper section of the snake to cover a portion of the central concave surface thereof and thus form a housing for a charge container 70 as shown in Figs. 18 and 19.

The charge container 70 comprises a metallic housing 71 which is adapted to fit within the shield and abut a steel wall 72 which extends vertically between the cover plate 69 and to a base plate 73 which is attached to an upper section of the snake. On the outer wall of the charge container 70 is mounted a striker pin 74 and horizontally extending rods 75 on which is mounted an impact plate 76. The impact plate is provided with holes 77 which fit over the rods 75, the plate being held in position by springs 78 and nuts 79. On the impact plate 76 is mounted a luminous button 80.

The explosive cartridge comprises a tubular metallic shell 88 closed at one end by a retaining cap 89 and at the other end by a cap 90 to which is attached an ignition tube 91, the latter extending within the interior of the shell 88.

The charge within the initiating unit shield 69 is ignited by impact of a bullet fired from a gun in the turret of the tank striking either the target button or the target plate and charges within the cartridge are ignited by the explosion within the charge container 70.

Both the towing yoke 26 and the pushing cable 31 may be raised out of operative posi-

tion by cables or ropes 81 and 82 which pass over pulley rollers 83 and into a convenient opening in the tank so that the lowering and raising of the towing yoke and pushing cable may be controlled by an operator inside of the tank where he is not exposed to danger.

The towing yoke is composed of arcuate member 84 adapted to engage the towing hook 20. The arcuate member is connected to the tank by a pair of links 85. The cable 81 is connected to the arcuate member 84 by a bail 86 and spring 87.

Having thus described my invention, what I claim as new and wish to secure by Letters Patent is:

1. A torpedo of the type described comprising an elongated container for explosive charges, said container being composed of upper and lower sections, provided with longitudinally extended corrugations therein and united adjacent their extremities by overlapping portions thereof which are bolted together, said corrugations in said sections providing explosive retaining courses, luminous target means in connection with said container for igniting said charges, and means in connection with the forward and rear portions of said container for attachment to a vehicle for movement of the torpedo to a selected place for operation.

2. A torpedo of the type described comprising an elongated container for explosive charges, said container being composed of a plurality of separable upper and lower sections having overlapping end portions, each section being detachably united to its adjoining section by fastening said overlapping end portions of the adjacent sections to each other, means formed integral with said sections for retaining explosive charges therebetween, luminous target means in connection with said container for igniting said charges, and a forward hook and a rear hook projecting from said container adapted to engage means for towing and pushing said torpedo to a selected place for operation.

3. A torpedo of the type described comprising an elongated container for explosive charges, said container being composed of a plurality of separable upper and lower sections provided with longitudinally extending corrugations therein providing explosive retaining courses, said sections being adapted to partially overlap adjacent sections, and having said head and tail portions provided respectively with upwardly projecting towing and pushing hooks, channel means formed by the corrugations in said sections providing explosive retaining courses, and luminous target means connected with said container and projecting upwardly therefrom for igniting said charges.

4. A torpedo of the type described comprising an elongated container for explosive charges composed of a plurality of separable upper and lower centrally connected overlapping metallic sections, formed of spaced strips provided with longitudinally extending corrugations therein and adapted to retain explosive charges between the channels formed by said corrugations, a head pivotally connected to one end of said container, said head comprising a conical body portion and a hemispherical end portion, a tail portion, a tail ramp connected to said tail portion, a towing hook and a pushing hook connected respectively to a forward and a rear section of said torpedo, and means comprising a target having a centrally located luminous button connected with said container for igniting said explosive charges.

5. A torpedo adapted to be towed and pushed into operative position by a vehicle, said torpedo comprising an elongated casing formed of a plurality of vertically spaced, upper and lower overlapping, longitudinally extending, corrugated metallic strips united centrally to form parallel channels extending throughout the length of the casing for the reception of explosive charges and a ballast, a yoke shaped nose adapter provided with parallel limbs, two of which are adapted to be inserted within the forward ends of said channels and retained thereby, and a third limb projecting forward of said casing, a nose member connected to said forwardly projecting limb and a tail ramp connected to the rear end of the casing, towing and pushing hooks, mounted upon said casing adjacent the forward and rear ends thereof, and target operated ignition means provided with a luminous button and mounted upon the upper surface of said casing for exploding the charges therein.
